VEGETABLE MASHER

Richard S. Latham, Chicago, Ill., assignor to American Home Products Corporation, New York, N.Y., a corporation of Delaware

Filed Dec. 3, 1965, Ser. No. 53

Term of patent 14 years

(Cl. D44—29)

FIG. 1 is a side elevational view of a vegetable masher showing my new design.

FIG. 2 is a section taken along line 2—2 of FIG. 1 with a portion in elevation.

FIG. 3 is a transverse section taken along line 3—3 of FIG. 1.

The dominant feature of my new design resides in the portion shown in full lines.

I claim:

The ornamental design for a vegetable masher substantially as shown and described.
